FUEL FEEDING DEVICE

Filed Sept. 22, 1928

UNITED STATES PATENT OFFICE

WILLIAM A. EDWARDS, OF CHICAGO, ILLINOIS, ASSIGNOR TO STEWART-WARNER CORPORATION, OF CHICAGO, ILLINOIS, A CORPORATION OF VIRGINIA

FUEL-FEEDING DEVICE

Application filed September 22, 1928. Serial No. 307,637.

The purpose of this invention is to provide an improved fuel feeding device for supplying an internal combustion engine, particularly adapted to utilizing the vapor of the fuel which under certain conditions is formed in the apparatus for offsetting the variation of the fuel mixture which sometimes results from air drawn into the intake manifold from the vacuum chamber while the suction valve is open. It consists in the elements and features of construction shown and described as indicated in the claims.

In the drawings:

Figure 1 is a diagrammatic view showing a vacuum tank embodying this invention in the position relative to the intake manifold and the carbureter.

Figure 2 is a vertical axial section of this fuel feeding device.

Figure 3 is a detail side elevation showing the float stem connection with the valve stem.

Referring to the drawing, the engine intake manifold is indicated at X, the carbureter at Y, and the vacuum tank in its entirety at Z.

In detail the vacuum tank comprises the outer or reserve chamber A and the inner or vacuum chamber B which is mounted telescopically within the upper part of the reserve chamber A, the construction for that purpose being that the reserve chamber A is closed at the top by cap member A¹, which is a metal stamping formed with a flange, fitting outside the upper end of the chamber A, this stamping being made to form a cylindrical shoulder q², and said cap having a central aperture indicated at a³, for admitting the vacuum chamber, B, which is dimensioned for fitting said aperture and has an out-turned flange, b¹, lapping the margin of the aperture, a³; and the chamber, B, is provided with a cap, B¹, having a down-turned marginal flange, b¹⁰, fitting outside the cylindrical shoulder, a², of the cap, A¹, of the outer chamber. Packing gaskets, b⁴, and b⁵, being interposed above and below the flange, b¹, screws, a⁶, serve to bind the parts together air-tight at their lapping flanges.

Since the outer chamber requires an atmosphere vent as hereinafter mentioned the

joint between the body, A, and cap A¹, need not be made air-tight and a snug fit, sufficient to prevent too easy or accidental displacement serves the purpose of permitting withdrawal of the inner chamber with the cap, A¹, carrying all operating parts, for any attention which they may require at any time. In the horizontal web of the cap, B¹, there is mounted the fuel inlet fitting, F, for connection with the fuel supply pipe, f, the inner end of the fitting, F, being adapted to hold a strainer, F¹.

At the center of said horizontal web there is mounted a fitting, E, for connection with the pipe, e, leading from the intake manifold, said fitting having a restricted passage, 20, leading to the suction port which is controlled by the suction valve, H, and in said fitting there is also formed an atmosphere inlet passage, 30, open to the atmosphere at 31 and leading to the valve seat, 32, at which the atmosphere valve, K, is arranged to seat downwardly.

The specific construction of this fitting will be understood from the drawings as comprising the outwardly projecting member, E, and two similar tubular members, E¹ and E², which project from the lower end of the member, E, constituting parallel prongs. The member, E, has two longitudinally extending parallel bores, e¹, e², which receive the upper ends of the prong members, E¹, E², which are tubular in form, having extending through them the suction and atmosphere passages, e³, e⁴, and being inserted and made tight preferably by drive fit in the bores, e¹ and e², into which the prong members extend for a short distance from the lower end of said bores, leaving above them an adequate portion of said bores to constitute chambers for the suction and atmosphere valves, H and K, of which the atmosphere valve seats at 32 at the upper end of the passage, e³, in said prong, E¹, the suction valve, H, seats upwardly at the shoulder, e⁵, constituting the valve seat formed by the reduced upper end portion of the bore, e², from which the duct, 20, leads to the end of the fitting which is ter-

minated suitably for connection with the pipe, e , to a source of suction.

The stems, h , k , of the suction and atmosphere valves respectively, extend down to 5 the suction and atmosphere passages, e^4 and e^3 , respectively, which have lateral apertures, e^{40} and e^{30} , for communication with the vacuum chamber, the stems, h and k , having guide bearings at e^{41} , and e^{31} , at the 10 lower ends of the prongs, E^1 and E^2 , from which respectively said stems extend for engagement with the stem, L , of the float, M , as hereinafter more particularly described.

The float, stem, L , is formed at its upper 15 end by bending in the form of a horizontally open hook seen at L^2 , the horizontally end of which enters between the two prongs, E^1 and E^2 , for guidance of the stem and float vertically. The range of vertical 20 movement of the float being such that not only this horizontally projecting terminal but also at the other side of the hook and the vertically extending portion of the stem move up between the two prongs when the 25 float rises to its upper limit.

It will be seen that the engagement as indicated of the float stem between the prongs, E^1 and E^2 , is adapted to check the float as to its sideward movement only in 30 one plane, and that for its complete guidance means must be provided for checking it in a transverse vertical plane. For that purpose the lower ends of the valve stems, h and k , which for their engagement with 35 the float stem have their lower ends bent for extending horizontally crosswise of the float stem for encounter with the vertically spaced shoulders constituting abutments on the float stem formed below the right angled 40 bends at l^2 and l^3 ,—are formed also for engagement with the float stem to check it bodily in planes transverse to that in which it is checked by said shoulders and between the prongs E^1 and E^2 , the form for this 45 purpose consisting of closed loops or eyes, h^4 and k^4 , as may be understood from the drawings.

The detail of construction and arrangement of the atmosphere and suction valves 50 and the fitting in which they are mounted and their connection with the float for operating, is not a part of the present invention the same being shown and fully described in the pending application of 55 Leonard H. Wheeler Ser. 131,861 filed Aug. 27, 1926, patented Apr. 29, 1930, No. 1,756, 895.

From the position of the float, M , in the chamber, B , it will be understood that the 60 outer reserve chamber in the casing member, A , at the annular portion of the chamber which surrounds the chamber, B , extends substantially higher than the high liquid level of the vacuum chamber, B , and at the 65 upper end of said annular part of the re-

serve chamber, A , there is provided an atmosphere vent indicated at a .

For the specific purpose of the present invention, from the upper end of this annular encompassing portion of the reserve chamber which encompasses the vacuum chamber, connection is made by pipe, R , with the fitting, E , outside the restricted passage, 20, and therefore outside the suction valve, H , said pipe, R , thus affording communication 70 of the reserve chamber, A , with the engine intake manifold from which suction is derived for operating the device for fuel lifting. In this communication there is provided a restriction indicated at r in the fitting by which the pipe R , is connected with the chamber A . This restriction has an aperture usually no larger than the restricted passage, 20, through which the vacuum 75 chamber derives suction from the intake 80 manifold.

The operation of this construction may be understood to be the usual and well understood operation of a vacuum tank having alternately opening atmosphere and suction 85 valves, namely that as the vacuum chamber is filled by suction from the lower source the rising of the float at a predetermined high level of the liquid closes the suction valve and opens the atmosphere valve permitting the liquid which has been lifted by suction into the chamber, B , to be discharged at the outlet valve, G , into the reserve chamber, A , until the lowering of the level of liquid in the vacuum chamber lowering the 90 float causes the latter to open the suction valve and close the atmosphere valve, whereupon the cycle is repeated.

In this operation, as is well understood, air more or less charged with fuel gases is 95 drawn from the vacuum chamber into the intake manifold while the suction valve is open, whereby under some circumstances the character of the fuel mixture is unfavorably affected for running the engine. In the construction herein described, this disturbance 100 of the fuel mixture is offset by fuel drawn through the pipe, R , from the upper part of the reserve chamber below the restriction, which is open throughout the entire operation but through which fuel vapor will be 105 drawn into the intake manifold substantially only during the period of discharge of the fuel from the vacuum chamber into the reserve chamber; because at that stage the disturbance of the liquid in the reserve chamber caused by the discharge into it from the 110 vacuum chamber, causes the vapor to be separated from the liquid in the lower part of the chamber and rise to the upper part, occupying the annular space at the upper 115 part above the high liquid level, from which it is drawn into the intake manifold during this part of the cycle, equalizing and offsetting the vapor which is drawn into the in- 120 125 130

take manifold at the suction valve when the latter is open.

I claim:—

1. An apparatus for lifting fuel for supplying an internal combustion engine which comprises a vacuum chamber and a fuel reserve chamber arranged to derive supply from the vacuum chamber at intervals during which the vacuum chamber is filled by suction, the vacuum chamber having an atmosphere inlet and a suction connection adapted to extend to a source of suction; a valve controlling said connection, automatically operating means for actuating said valve, and a duct affording restricted communication from the reserve chamber at a point therein above the high liquid level thereof to the suction connection and communicating with the latter at a point therein outward from said suction controlling valve.

2. In an apparatus for lifting fuel for supplying an internal combustion engine which comprises a vacuum chamber and a fuel reserve chamber arranged to derive supply from the vacuum chamber at intervals alternating with intervals during which the vacuum chamber is filled by suction, the vacuum chamber having an atmospheric inlet and a valve controlling the same, and a suction connection adapted to be extended to a source of suction and automatic means for operating said valves to alternate the access of suction and atmospheric pressure to the vacuum chamber, and a duct affording restricted communication from the reserve chamber at a point therein above the high liquid level thereof to the suction connection and communicating with the latter at a point therein outward from the suction controlling valve.

3. In an apparatus for lifting fuel for supplying an internal combustion engine which comprises a vacuum chamber and a fuel reserve chamber arranged to derive fuel supply from the vacuum chamber at intervals alternating with intervals during which the vacuum chamber is filled by suction, the vacuum chamber having an atmosphere inlet and a suction connection adapted to extend to a source of suction, a valve controlling said suction connection, means controlled by change of level of the fuel in the vacuum chamber for operating said valve, a duct affording restricted communication from the reserve chamber above the high liquid level of the latter to the suction connection and communicating with the latter at a point therein outward from the suction controlling valve, the reserve chamber having a part extending above the high liquid level of the vacuum chamber which is in free liquid communication with the lower part of said reserve chamber, whereby said duct serves for admitting to

the suction source fuel having vapor which may be formed in the reserve chamber.

4. In an apparatus for lifting fuel for supplying an internal combustion engine which comprises a vacuum chamber and a fuel reserve chamber arranged to derive fuel supply from the vacuum chamber at intervals alternating with intervals during which the vacuum chamber is filled by suction, the vacuum chamber having an atmosphere inlet, and a suction connection; adapted to extend to a source of suction, a valve controlling said connection; means controlled by a change of level of fuel in the vacuum chamber for operating said valve, a duct affording restricted communication from the upper part of the reserve chamber to the suction connection and communicating with the latter at a point outward from the suction controlling valve, the vacuum chamber being inserted into the upper part of the reserve chamber with space of the latter encompassing the vacuum chamber of substantial width for free and undelayed rise of the liquid fuel thereunto, said space extending a substantial distance above the high liquid level of the vacuum chamber for accumulating vapor of the fuel formed in the reserve chamber at a point whence it may find escape to the suction source.

5. An apparatus for lifting fuel for supplying an internal combustion engine comprising a vacuum chamber and a fuel reserve chamber arranged to derive supply from the vacuum chamber at intervals between periods during which the vacuum chamber is filled by suction, the vacuum chamber having an atmosphere inlet and connection with a source of suction, a valve controlling the atmosphere inlet, and automatic means for operating it; and a duct affording restricted communication between the reserve chamber at a point therein above the high liquid level thereof and the suction connection, whereby suction from the source of suction may operate to withdraw fuel vapor from the upper part of the reserve chamber to the source of suction.
